United States Patent Office.

JOHN MERLETT, OF BOUND BROOK, NEW JERSEY.

Letters Patent No. 63,738, dated April 9, 1867; antedated April 1, 1867

IMPROVEMENTS IN SPIKES.

The Schedule referred to in these Letters Patent and making part of the same.

TO ALL WHOM IT MAY CONCERN:

Be it known that I, JOHN MERLETT, of Bound Brook, in the county of Somersét, and State of New Jersey, have invented certain new and useful Improvements in Spikes; and I do hereby declare that the following is a full, clear, and exact description of the same, reference being had to the accompanying drawings, making a part of this specification, in which—

Figure 1 is a side view of a spike constructed according to my invention.

Figure 2 is a side view of the same at right angles to fig. 1.

Similar letters of reference indicate corresponding parts in both figures.

This invention relates more especially to railroad spikes, and it consists in a novel construction of a spike whereby it is prevented from being drawn out of the wood into which it may be driven, and whereby the entrance of moisture between the spike and the wood surrounding the same, and consequently the premature decay of the wood and the corrosion of the spike resulting therefrom, are effectually prevented.

To enable others to understand the construction and operation of my invention, I will proceed to describe it with reference to the drawings.

A represents the body of the spike, which is made four-sided, with two of its opposite sides made tapering or inclined at its lower end, as shown at *a*, so that the lower end of the spike is brought to a cutting edge, as at *b*. Formed upon and projecting out from each of these inclined sides of the lower end of the spike is a tapering or wedge-shaped rib, *c*, the upper end of which forms a square shoulder, *c'*, situated at right angles to the side of the body of the spike, as shown more clearly in fig. 2. Formed upon and projecting out from each of the two remaining or flat sides of the lower end of the spike is a similar wedge-shaped rib, *d*, the lower end of which forms a portion of the cutting edge *b* at the lower end of the spike, and the upper end of which constitutes a shoulder, *d'*, corresponding to the shoulders *c'* of the ribs *c*. B is the oblong head of the spike, which, when the spike is used, acts upon the flange of the rail to hold the rail in place in the same manner as the heads of the spikes in ordinary use. The side *f* of the spike from which the greatest length of the head *B* projects is made plain and straight clear up to the said head, but formed upon the remaining three sides of the spike at a little distance below the said head is a long outwardly projecting lug, *g*, the three outer sides or faces of which are made sloping or inclined inward toward their lower edges, as shown at *g'* in fig. 1, and the under sides of which are formed at an acute angle to the sides of the body of the spike, so that the lower edge of the said lug *g* constitutes a cutting edge, *n'*. The spike is driven into the wooden tie or sleeper in the usual manner, with the longest portion of its head, *B*, placed upon the flange of the rail, as hereinbefore mentioned, the absence of a lug upon the side *f* allowing the body of the spike to be brought closely against the edge of the said flange. The spike being thus driven into the wood, the expansion of the wood inward over the shoulders *c'* and *d'* of the ribs *c* and *d* effectually prevents the spike from being retracted or withdrawn. Furthermore, as the spike is driven downward the cutting edge *n'* of the lug *g* smoothly cuts away the wood lacerated by the passage of the ribs on the sides of the spike on which the said lug is formed in such manner that as the spike is driven down the inclined outer sides of the said lug are caused to fit against the surrounding wood, near the upper surface thereof, with sufficient tightness to prevent the entrance of water between the wood and the upper part of the spike, thus obviating all danger of the decay of the wood from the presence of moisture around the spike, and also, in a great measure, the oxidation and corrosion of the spike itself from the same cause.

What I claim as new, and desire to secure by Letters Patent, is—

1. The wedge-shaped ribs *c* *d*, forming shoulders *c'* *d'* at their upper ends, and arranged upon the lower portion of the spike, substantially as herein set forth for the purpose specified.
2. The lug *g*, constructed with a cutting edge, *n'*, and with inclined sides *g'*, in combination and arranged in relation with the wedge-shaped ribs *c* *d* and with the body of the spike, substantially as herein set forth for the purpose specified.
